(57) CLAIM

The ornamental design for a folding chair, as shown and described.

DESCRIPTION

FIG. 1 is a front, right, top perspective view of a folding chair, showing my new design;

FIG. 2 is a rear, left, bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of the encircled portion labelled 9 in FIG. 1; and,

FIG. 10 is an enlarged view of the encircled portion labelled 10 in FIG. 1.

The broken lines shown in the drawings illustrate portions of the folding chair that form no part of the claimed design.

1 Claim, 10 Drawing Sheets
